UNITED STATES PATENT OFFICE.

SETH H. GAGE, OF AMESBURY, MASSACHUSETTS, ASSIGNOR OF ONE-HALF TO FREDERICK H. ROWE, OF LYNN, MASSACHUSETTS.

HINGE-LOCK.

1,226,324.

Specification of Letters Patent. Patented May 15, 1917.

Application filed February 10, 1915. Serial No. 7,361.

To all whom it may concern:

Be it known that I, SETH H. GAGE, a citizen of the United States, residing at Amesbury, county of Essex, State of Massachusetts, have invented an Improvement in Hinge-Locks, of which the following description, in connection with the accompanying drawing, is a specification, like characters on the drawing representing like parts.

This invention relates to hinge locks. More particularly does it involve an automatically or self-locking hinge.

While it is obvious that this hinge lock is of divers utilities and that this invention may be embodied in different adaptions, it is especially useful in connection with present-day motor and other vehicle tops. The braces or vehicle tops, which of necessity in modern usage must be foldable, have a tendency to sag at the hinged folds. And, in the endeavor to overcome this objection, various combinations comprising pulleys and cords, buckles and straps, non-flexible supports and sockets therefor, have been evolved to effect the rigid retention of these top braces. These devices have proved more or less efficient, but through the trend of manufacturers to produce what are known in the motor vehicle trade as "one-man tops", these devices are ineffective and cannot be efficiently employed. It is therefore requisite that in this construction a hinge be employed which may be easily opened and will automatically lock in rigid open position and, further, it is essential that the lock be easily disengaged.

The object of this improved construction is to produce a self-acting lock for a hinge, adapted rigidly to retain the hinge in locked open position and capable of facile and simple disengagement.

Other objects of the invention will more fully appear from the following description and the accompanying drawings and will be pointed out in the annexed claims.

A selected embodiment of the lock as affixed to a common type of hinge has been illustrated in the accompanying drawings and will now be described.

Figure 1 is a perspective view of the hinge lock in semi-open unlocked position, showing a plurality of central slots in dotted lines;

Fig. 2 is a perspective of the hinge lock in open locked position;

Fig. 3 is a plan of the view shown in Fig. 1 with the trigger and spring removed;

Fig. 4 is a perspective of the trigger.

The hinge is composed of two hinge members 1 and 2. One member 1 is formed with a pair of opposed ears 3, 3 preferably integral with its body portion and, solely for the purpose of facility in description, this member 1 is referred to as the relatively fixed member. These ears are formed offset from the portion 4. The other hinge member 2 bears at its end portion 5, and preferably integral therewith, a single similar offset ear 6. These ears are all centrally bored and are pivotally secured by means of a suitable pintle 7, the single ear being embraced by the pair of ears. The fixed member has cut therein, at its end and between the opposed ears, a channel 8 which forms a runway for the single ear 6, permitting ease of rotation about the pintle. The end of the other hinge member 2 is arcuately cut away on both sides adjacent to the single ear and a path 9 is thus presented for facile movement of this relatively movable hinge member 2 about the periphery of the double ears.

The peripheries of the twin opposed ears carried by the member 1 have transverse slots 10 cut therein which are in alinement and are adjacent the shoulder 11 of this member. The ear 6 of the member 2 has a peripherally transverse slot 12 cut therein adjacent its shoulder 13 so that when the hinge members are alined in substantially the same horizontal plane as shown in Fig. 2, the slots in the twin ears and the slot 12 are in transverse registry. The single ear 6 may also have, as shown in this selected embodiment, a plurality of similar peripheral slots 14 and 15, whereby the hinge may be locked in diversified positions.

As the peripheral slots in the twin ears are formed adjacent the shoulder 11 of the member 1, this shoulder 11 functions substantially as a prolongation of the slot and, when the slots are in registry as shown in Fig. 2, the shoulder 13 of the relatively movable member 2 with its ear slot adjacent thereto functions substantially as a prolongation of the other side of the slot.

The locking member is actuated by a spring 16 which consists, in this selected

embodiment, of a piece of flat strip spring steel the rear portion of which is secured to the hinge member 1 by means of a screw 17 engaging a threaded recess 18 bored therein. The forward portion of the spring 16 preferably strengthened by folding the strip upon itself, rendering it a better resistant to sheering stress, forms the latch 19. This reinforced portion or latch is of such length and is bent at such an angle as will allow its seating in the locking slot formed by the transverse alinement of any three peripheral slots. Such spring steel stock is preferably employed as will, when doubled, substantially completely occupy the locking slot. The reinforced latch when in normal locked position in registering slots forms an intermediary against which, when the hinge members are in open or alined position, the shoulders 11 and 13 of the hinge members 2 and 1 may impinge—thus functioning to prevent the hinge members from swinging beyond substantially horizontal alinement on the side opposite the ears. A simple and effectual means is provided for manually unlocking the hinge members which, in this preferred form, consists of an eccentric stud 20. The body portion of this stud is of a configuration substantially lunate in cross section having a curved face 21 and a flat face 22. One end of the stud terminates in a flattened head 23 while the other has, preferably integral therewith, a handle or trigger 24. This eccentric stud is adapted normally to seat in the arcuate depression 25 in the hinge member 1 adjacent its shoulder 11. In this normal or locked position the curved face 21 of the stud fits in the depression 25 while its flat face 22 is presented to the spring 16. The tension of the spring effectuates the retention of the stud in such position as well as the retention of the reinforced latch portion in engagement with the locking slot. The trigger 24 has a tip 26 which is bent and extends over the surface of the spring.

As embodied in motor vehicle "one-man top" construction this improved hinge has only one transverse slot 12, on its single ear 6. Thus, in operation, when it is desired to unlock the hinge, the trigger tip 26 is pressed down upon the surface of the spring, and the stud is partially rotated. This rotary movement effectuates the lifting of the latch member against the tension of the spring. The latch member being lifted from engagement with the locking slot the hinge may be broken or turned. The latch member then is upheld out of reengagement with the transverse slots 10 in the twin ears 3 by the unslotted circumference of the ear 6 embraced between the two ears. The latch member travels over the periphery of the single ear as the hinge is turned—always

under tension of the spring tending to force it thereupon. The stud is then seated loosely in the depression but is retained against lateral movement by the flat head 23 and the trigger arm. The hinge members can in this form, be completely turned back upon each other and form a compact flush and space-economizing fold.

When it is desired to secure the hinge members in unfolded and locked position, the hinge members are opened, the latch member again travels over the periphery of the single ear until the three transverse slots register, forming the locking slot, into which the latch member drops under the tension of the spring member. The spring member, which was held above the eccentric stud again presses thereupon, forcing it into normal seated position ready for manually effected unlocking.

It is to be noted that the trigger is bent over the surface of the spring. This construction is preferred as the relation of the travel of the trigger before its tip 26 impinges upon the surface of the spring and the degree of movement imparted to the cam surface of the eccentric stud may be so made that the stud can not be turned to such position that it will become wedged or jammed and its automatic re-seating in normal inoperative position in the depression be hindered.

This novel hinge lock is also adapted for use in connection with wind shields and such devices where it is essential to have a hinge adapted to lock automatically in a plurality of positions. In such construction the requisite number of transverse peripheral slots are cut in the single ear 6. In the embodiment selected, such slots 14 and 15 are shown. In the operation of this construction, the trigger is depressed from normal locked position, the latch, raised from the locking slot formed by the registry of the twin ear slots 10 and the slot 12, then travels upon the circumference of the ear 6 until the slot 14, transversely alined with the slots 10, forms another locking slot into which the latch is forced by the spring 16.

There is thus produced a novel self-acting hinge lock of few parts, which is efficient, durable, inexpensive to manufacture and is of the greatest simplicity of operation.

It is to be understood that the construction disclosed herein is merely illustrative and not restrictive and that the same may be modified within the meaning and scope of the claims which follow.

Having fully described my invention, what I claim as new and desire to secure by Letters Patent is:

1. A hinge lock comprising a pair of shouldered members having pivotally connected ears, co-operating locking means on each of said ears, and a resilient locking

member adapted simultaneously to engage said locking means.

2. A hinge lock comprising a pair of shouldered members, one having a pair of separated cylindrical ears and the other member having a centrally disposed complementary ear adapted to be positioned between the separated cylindrical ears, said pair of ears having a plurality of peripheral alined slots and said centrally disposed ear being peripherally slotted, pivotal means connecting said ears whereby upon relative movement between the pair of ears and the central ear all slots may be alined, and locking means movable simultaneously to engage all slots when in alinement.

3. A hinge lock comprising a pair of members having pivotally connected ears, peripheral locking means on said ears, and a resilient locking member L-shaped in form having a shorter arm folded upon itself to reinforce and stiffen the same, said shorter arm being adapted simultaneously to engage said locking means whereby the hinge is locked.

4. A hinge lock comprising a pair of members having pivotally connected ears, peripheral locking means on said ears, a strip spring on one of said members having a bent stiffened portion adapted simultaneously to have tensioned locking engagement with said locking means.

5. A hinge lock comprising a pair of

members having pivotally connected ears, a leaf spring secured to one of said members, 35 a latch segment formed by an integral bent portion of said spring and means on said ears adapted to receive said latch segment whereby said hinge members may be simultaneously engaged.

6. A hinge lock comprising a pair of members having pivotally connected ears having peripheral transverse slots therein, a leaf spring secured to one of said members, and having a reinforced integral latch portion adapted under tension to engage alined slots in said ears.

7. A hinge lock comprising a pair of members having pivotally connected ears having peripheral transverse slots therein, 50 a resilient element carried by one of said members, a latching means on said element to engage said slots when transversely alined, said element-carrying member being recessed, an eccentric movably seated in said recess normally out of operable engagement 55 with the resilient element, and movable to disengage the latching means from the slots.

In testimony whereof, I have signed my name to this specification, in the presence 60 of two subscribing witnesses.

SETH H. GAGE.
